(57) **CLAIM**

We claim the ornamental design for a rear projection television, as shown and described.

DESCRIPTION

FIG. 1 is a front perspective view of a rear projection television of the present invention;
FIG. 2 is a rear perspective view thereof;
FIG. 3 is a front view thereof;
FIG. 4 is a first side view thereof;
FIG. 5 is a rear view thereof;
FIG. 6 is a second side view thereof;
FIG. 7 is a top view thereof; and,
FIG. 8 is a bottom view thereof.
